UNITED STATES PATENT OFFICE

ERWIN HOFFA AND FRITZ MÜLLER, OF FRANKFORT-ON-THE-MAIN-HOCHST, GERMANY, ASSIGNORS TO GENERAL ANILINE WORKS, INC., OF NEW YORK, N. Y., A CORPORATION OF DELAWARE

PROCESS OF PREPARING HYDROXYTHIONAPHTHENES

No Drawing. Application filed August 2, 1928, Serial No. 297,102, and in Germany August 17, 1927.

Our present invention relates to a new process of preparing hydroxythionaphthalenes.

It has hitherto been unknown to prepare arylcarboxylic acid amide-ortho-thioglycolic acids of the general formula:

wherein R stands for an unsubstituted or substituted aromatic residue by an alkaline saponification of cyanoaryl-ortho-thioglycolic acids of the general formula:

wherein R stands for an unsubstituted or substituted aromatic residue.

It had been assumed that the arylcarboxylic acid amide-ortho-thioglycolic acids would be formed as intermediary products during the transformation of cyanoaryl-ortho-thioglycolic acids into aminothionaphthalene carboxylic acids. This view has, however, proved to be erroneous since it has been ascertained that by the action of alkali the arylcarboxylic acid amide-ortho-thioglycolic acids are not converted into aminothionaphthalene carboxylic acids but into hydroxythionaphthalene carboxylic acids (cf. the co-pending U. S. patent application Ser. No. 211,852 filed by Erwin Hoffa, Jens Müller and Fritz Müller on August 9, 1927).

We have now found that the preparation of arylcarboxylic acid amide-ortho-thioglycolic acids from cyanoaryl-ortho-thioglycolic acids can also be effected in an alkaline solution by causing hydrogen peroxide to act upon such solutions. The saponification of nitriles by means of alkali and hydrogen peroxide is as such known and described for instance in "Journal für Praktische Chemie" volume 93, page 137. It was, however, not to be foreseen that this process could also be applied to the above-described purpose, as it has been known that by the action of an alkali cyanoaryl-ortho-thioglycolic acids are transformed into aminothionaphthalene carboxylic acids.

Apart from the chemical novelty of the process it affords considerable technical advantages. It is no longer necessary to isolate

the resulting arylcarboxylic acid amide-ortho-thioglycolic acid which can now be transformed into the hydroxythionaphthene in the same solution in which it has been formed, by a further alkaline treatment according to the process described in the U. S. application Ser. No. 211,852 above referred to. Thus a way has been found for preparing hydroxythionaphthalenes from cyanoaryl-ortho-thioglycolic acids in a technically simple manner and in a single operation.

The following examples illustrate our invention, but they are not intended to limit it thereto. The parts are by weight:

1. 23.7 parts of 2-cyano-5-ethoxybenzene-1-thioglycolic acid are dissolved in a solution of 8 parts of caustic soda in 100 parts of water while heating to 40° C. and to this solution are added 100 parts of a 3% solution of hydrogen peroxide. The mixture is further heated, another 100 parts of a 3% solution of hydrogen peroxide being gradually run in. The temperature is raised to 70° C. and maintained there for some time. By acidifying the solution, the carboxylic acid amide which has been formed can be precipitated.

The reaction takes place according to the following equation:

However, when carrying out the reaction for the purpose of forming the hydroxythionaphthene, one may dispense with the isolation of the carboxylic acid amide. 8 parts of caustic soda are added to the solution and the whole is heated to 95° C. for 6 to 7 hours in the manner described in the afore-mentioned U. S. application Ser. No. 211,852, until the evolution of ammonia has ceased. The solution is then acidified and the resulting 6-ethoxy-hydroxythionaphthene is filtered by suction. 100

2. 24.2 parts of 5-chloro-1-methylbenzene-2-cyano-3-thioglycollic acid and 8 parts of caustic soda are dissolved in 300 parts of water. 100 parts of a 3% solution of hydrogen peroxide are added to this solution at 5 30° C. and the mixture is heated to 40° C. for 1½ hours. The solution is then quickly heated to 70° C., 50 parts of a 3% solution of hydrogen peroxide being added thereto at 10 60° C. and another 50 parts at 70° C. At 70° C. there is then introduced in the course of half an hour a further quantity of 100 parts of a 3% solution of hydrogen peroxide and after the evolution of oxygen has decreased, the whole is acidified with hydrochloric acid. The product of the reaction is 15 filtered by suction and washed with a small quantity of water and then with ether. It is the 2-carboxylic acid amide of 1-methylbenzene-5-chloro-3-thioglycollic acid-2-carboxylic acid, melting at 172° C.

We claim:

1. The process of preparing hydroxythionaphthalenes which consists in saponifying a 25 cyanoaryl-ortho-thioglycollic acid of the formula:

30 wherein R stands for an unsubstituted or substituted aromatic hydrocarbon residue, by the action of hydrogen peroxide in an alkaline solution so as to form the corresponding arylcarboxylic acid-amide-ortho-thioglycollic acid of the formula:

40 wherein R stands for an unsubstituted or substituted aromatic hydrocarbon residue, and transforming the latter by the further action of an alkali into the hydroxythionaphthalene.

45 2. The process of preparing hydroxythionaphthalenes which consists in saponifying at a temperature of between 40° C. and 70° C. a cyanoaryl-ortho-thioglycollic acid of the formula:

50 wherein R stands for an unsubstituted or substituted aromatic hydrocarbon residue, by the action of hydrogen peroxide in an alkaline solution so as to form the corresponding arylcarboxylic acid-amide-ortho-thioglycollic acid of the formula:

60 wherein R stands for an unsubstituted or substituted aromatic hydrocarbon residue, and transforming the latter by the further action of an alkali into the hydroxythionaphthalene.

65 3. The process of preparing 6-ethoxyhydroxythionaphthalene which consists in sa-

ponifying 5-ethoxy-2-cyanobenzene-1-thioglycollic acid by the action of hydrogen peroxide in an alkaline solution as to form 5-ethoxy-benzene-2-carboxylic acid amide-1-thioglycollic acid and transforming the latter by the action of an alkali into the 6-ethoxyhydroxythionaphthalene.

4. The process of preparing 6-ethoxyhydroxythionaphthalene which consists in saponifying at a temperature of between 40° C. and 75 70° C. 5-ethoxy-2-cyanobenzene-1-thioglycollic acid by the action of hydrogen peroxide in an alkaline solution so as to form 5-ethoxybenzene-2-carboxylic acid amide-1-thioglycollic acid and transforming the latter by the 80 action of an alkali into the 6-ethoxyhydroxythionaphthalene.

In testimony whereof, we affix our signatures.

ERWIN HOFFA.
FRITZ MÜLLER.
